R. KERSTEN.

APPARATUS FOR WASHING OR DEVELOPING PHOTOGRAPHIC PLATES OR FILMS.
APPLICATION FILED DEC. 17, 1915.

1,234,346.

Patented July 24, 1917.

Inventor
Rudolf Kersten

By his Attorney
W. A. St. John

UNITED STATES PATENT OFFICE.

RUDOLF KERSTEN, OF DRESDEN, NORTH DAKOTA.

APPARATUS FOR WASHING OR DEVELOPING PHOTOGRAPHIC PLATES OR FILMS.

1,234,346.

Specification of Letters Patent.

Patented July 24, 1917.

Application filed December 17, 1915. Serial No. 67,398.

To all whom it may concern:

Be it known that I, RUDOLF KERSTEN, citizen of the United States, intention declared, residing at Dresden, in the county of 5 Cavalier and State of North Dakota, have invented certain new and useful Improvements in Apparatus for Washing or Developing Photographic Plates or Films, of which the following is a specification.

10 The present invention relates to apparatuses for washing or developing photographic plates or films and has for its object to provide a construction whereby a number of photographic plates or films can 15 be simultaneously quickly and efficiently washed or developed.

With this object in view my invention consists in the construction, combination and arrangement of parts, as will be hereinafter 20 fully specified and set forth in the appended claims.

In the accompanying drawing, which forms part of this specification and in which similar reference characters denote corresponding parts, Figure 1 is a longitudinal section of my apparatus; Fig. 2 is an enlarged section on line 2—2 of Fig. 1 and Fig. 3 is a top plan view of a detail.

In the drawing a denotes a tank of metal 30 or other suitable material and which may be either cylindrical as shown or of other suitable shape. This tank has on top a removable cover or lid a' provided with a funnel a^2 and at its bottom a flow off valve or cock a^3 . When the apparatus is used for washing 35 it may be placed under a faucet, so that on opening the valve the water may freely circulate therethrough.

Revolutionarily borne in the tank is a central 40 horizontal spindle b which at one end projects outwardly from the tank and carries a crank arm b' whereby the spindle can be manually rotated. The part of the spindle extending within the tank is preferably of 45 polygonal shape and is provided on each side of its circumference with two or more dovetailed grooves or sockets c . Adapted to be removably secured in the said sockets are rectangular frames d , having open faces and

of which each on one of its longitudinal 50 edges is provided with tenons or dove-tailed projections e adapted to snugly fit in the said sockets. These frames may be each divided in two compartments, d' , d^2 each compartment serving to receive a photographic plate or film h . The openings d^3 through which the plates or films are inserted into the compartments of the frames, are adapted to be closed by slides f borne in grooves d^4 made in the walls of the frames. 60 The frames when secured to the spindle extend in radial direction from the latter and will be caused to revolve around the axis of the spindle when the latter is rotated. Thereby the plates or films contained in the 65 frames and having their sensitive faces exposed to the liquid circulating through or filling the tank will become thoroughly washed or developed as the case may be.

One advantage of my novel construction 70 is that a great number of plates or films, say a dozen at a time, can be most effectively, quickly and uniformly treated.

Another advantage is that since the frames can be easily removed from the 75 spindle, the same may be easily exchanged for smaller or larger ones to accommodate variously sized plates or films. Thus the same apparatus can be employed for plates or films of various sizes.

While I have described one embodiment 80 of my invention, it is understood that since various modifications may be made in the construction without deviating from the principle of my invention, I do not limit 85 myself to the details described and shown.

What I claim and desire to secure by Letters Patent is:

1. A washing or developing apparatus for photographic plates or films, comprising a 90 tank, a spindle revolutionarily borne in said tank and having sockets on its circumference and frames removably held in said sockets for holding said plates or films so that by turning the spindle the plates or films will be 95 moved through the liquid in the tank.

2. A washing or developing apparatus for photographic plates or films, comprising a

tank, a polygonal spindle revolvably borne in said tank and having sockets on each side of its circumference, and frames removably borne in said sockets for holding said plates 5 or films.

3. A washing or developing apparatus for photographic plates or films, comprising a tank, a spindle revolvably borne in said tank and having dove-tailed sockets on its circum-

ference, and frames for holding said plates 10 and films removably borne in said sockets.

In testimony whereof I affix my signature in presence of two witnesses.

RUDOLF KERSTEN.

Witnesses:

J. A. TERHAAR,
A. J. EVELAGE.
